UNITED STATES PATENT OFFICE.

JOHN W. RAYMOND, OF RACINE, WISCONSIN.

DESIGN FOR A CASING FOR ENGINES.

SPECIFICATION forming part of Design No. 26,566, dated January 26, 1897.

Application filed January 13, 1896. Serial No. 575,383. Term of patent 3 years.

To all whom it may concern:

Be it known that I, JOHN W. RAYMOND, a citizen of the United States, residing at Racine, in the county of Racine and State of Wisconsin, have invented and produced a new and original Design for Engine-Casings; and I do hereby declare the following to be a full, clear, and exact description of the same, reference being had to the accompanying drawings, forming a part thereof.

My invention relates to a new and original design for engine-casings, and is illustrated in the accompanying drawings, in which—

Figure 1 is a side elevation of an engine embodying my design. Fig. 2 is an end view of the same.

The leading features of my design consist in a base portion provided with outwardly curved flanges, said base portion being tapered or inclined inwardly upon all sides toward its top and terminating in an inwardly curved or arched upper edge, from which rises a second or intermediate portion having vertical sides, but of smaller dimensions than the upper part of the lower or base portion and being likewise inwardly curved or arched at its upper edge, and from which in turn rises a third or top portion of the casing similarly curved or arched inwardly at its upper edge and having a horizontal top or cover.

Upon one side of the lower part of the casing is provided an approximately oval man-hole with a cover-plate bolted or otherwise

secured thereto, and upon the opposite side is provided an upwardly-curved pipe.

35

The particular form of my engine which I have shown in the drawings and herein described is a four-cylinder gas-engine, and in such a structure the casing presents, when viewed from above, a generally oblong appearance with rounded or curved ends. When a less number of cylinders are employed, the casing will be of proportionately shorter length, but of the same general appearance and construction, and I would have 40 it understood that my design, as herein described, is intended for application to the casings of engines having one or a plurality of cylinders, as may be desired, said design consisting, essentially, in the particular conformation of the exterior casing or cover of the engine, which comprises the lower, the intermediate, and the upper portions, successively diminishing in size from bottom to top and presenting inwardly curved or arched 45 edges or shoulders where the portions of the casing are joined together.

50

What I claim is—

The design for an engine-casing herein shown and described.

60

In testimony whereof I affix my signature in the presence of two witnesses.

JOHN W. RAYMOND.

Witnesses:

JOHN E. WILES,
H. J. ROGERS.
